UNITED STATES PATENT OFFICE.

JOHN W. FOSTER, OF FALL RIVER, MASSACHUSETTS.

MACHINE FOR WINDING BOBBINS.

SPECIFICATION forming part of Letters Patent No. 436,521, dated September 16, 1890.

Application filed November 5, 1889. Serial No. 329,860. (No model.)

To all whom it may concern:

Be it known that I, JOHN W. FOSTER, of Fall River, county of Bristol, State of Massachusetts, have invented an Improvement in 5 Machines for Winding Bobbins, of which the following description, in connection with the accompanying drawings, is a specification, like letters and figures on the drawings representing like parts.

10 This invention is an improvement on that contained in United States Patent No. 404,831, granted to me June 11, 1889, to which reference may be had.

In the patent referred to the spool on which 15 the yarn is wound rests on a drum interposed between the said spool and a rotating driving-cylinder, the said drum taking up considerable space, and to arrest the rotation of the 20 spool when full or in case the yarn breaks the said drum is lifted automatically by devices also requiring considerable space.

In my efforts to improve and simplify the construction of the machine described in the 25 said patent, and at the same time reduce its cost of manufacture and the power required to run it, I have discovered that I may dispense with the solid drums referred to and accomplish the purpose effected by the drums by the employment of a thin metallic hollow 30 shell surrounding the said driving-cylinder and actuated by it to rotate the spool or other device resting thereon and on which the yarn is to be wound.

In accordance with my invention the hollow shell surrounding the said cylinder and 35 having an internal diameter a little greater than the external diameter of the driving-cylinder is rotated by the said driving-cylinder so long as the said shell rests upon the said 40 cylinder; but whenever the said shell is slightly lifted, so as to place its longitudinal center coincident with the center of rotation of the said cylinder, then the contact between the inner side of the shell and the outer side 45 of the driving-cylinder is broken, and as a result thereof the rotation of the said shell is instantly stopped, and with it a spool or device lying on it, the driving-cylinder continuing to rotate.

50 In my present machine, owing to the omission of the drums referred to, it is possible to locate the shafts carrying the driving-drums

above the rail, where they may take bearing in the spool-stands rather than in independent stands below the rails, thus enabling the 55 said shafts and cylinders to be in plain sight and accessible.

My invention consists in the combination, with a rotating cylinder and a surrounding rigid shell adapted to be rotated thereby, of 60 means to lift or suspend the said shell out of contact with the said cylinder when it is desired to stop the rotation of the said shell; also, in the combination, with stands, cheek-pieces to hold a spool and permit it to be rotated in the said stands, a shaft, a cylinder thereon, and rigid shell surrounding the said cylinder and adapted to support the said spool, of means to lift or suspend the said shell from contact with the said cylinder when 70 it is desired to stop the rotation of the said spool; also, in the combination, with a rotating cylinder, of a hollow shell surrounding it and rotated by the said cylinder by frictional contact.

75 Other features of my invention will be described in this specification and pointed out in the claims at the end thereof.

Figure 1, in section and elevation, shows a sufficient portion of one side of a winding or 80 spooling machine with my improvement added to enable my invention to be understood. Fig. 2 is a partial section in the line α , Fig. 1, the shell and cylinder being in driving contact; Fig. 3, a similar section, showing the 85 shell and cylinder out of driving contact; and Fig. 4 is a detail of part of the stop-motion devices.

The frame-work consists of suitable end pieces A (but one shown) and suitable rails or girts A² A³. The rails A² A³ are arranged in pairs; but, as the parts to be carried by them are just alike, I shall only illustrate said parts on the rails A². The rails A² have bolted to them stands a b, arranged in pairs, 90 the upper slotted ends of which receive the end journals of a suitable shaft or of cheek-pieces c c on or between which to hold the spool or device d on which the yarn is to be wound. The upper part of the stand b is 95 adapted to be turned over, together with its cheek-piece, when it is desired to remove or apply a spool.

The cylinder e is herein shown as composed

of two annular disks fixed to a shaft e' ; but instead the said cylinder may be in one piece as long as the barrel of the spool, it, when made in two short sections, as shown, being 5 lighter. The shaft e' , taking its bearings in the stands a b , has a pulley e^2 , about which is placed a belt e^3 , surrounding a pulley e^4 on the main shaft e^5 , which may be rotated in any usual way.

10 The spring f , connected to the upper and lower ends of the stand b , aids in keeping the upper part of the stand either in its upright position or turned over about the hinge 2.

15 The girt A' has two uprights g g , in which rests the slide g' , having pivoted on it the stop-motion latch g^3 , beneath which on said slide are the two stops 3 4, the slide being surrounded by a spring g^2 normally to push the same to the right in Fig. 1.

20 The rotating ratchet-shaft 34 has a ratchet-wheel 33, one for each cylinder, so that whenever a drop-wire (not shown, but of any suitable construction) drops on the outer or left-hand end of the latch g^3 , (see Fig. 1,) which 25 happens whenever a yarn breaks, it lifts the inner or right-hand end of the said latch, so that the ratchet-wheel strikes the latch and pushes the slide g' to the left, viewing Fig. 1, to thereby effect the stopping of any spool.

30 The parts so far described, with the exception of the cylinder, composed, as shown, of two disks, and the particular shape of the inner end of the slide g' , to be further described, and the location of the shaft e' are 35 all substantially as in the said patent. The cylinder e on the shaft e' is surrounded by a hollow shell h , preferably of metal; but it may be of other rigid material. When the shell h surrounding the said cylinder, as shown,

40 rests with its weight thereon, as in Fig. 2, the rotation of the cylinder acts to rotate the said shell, and the latter rotates the spool or equivalent device resting thereon. The internal diameter of the shell shown is a little greater 45 than the external diameter of the cylinder e , and the length of the shell is sufficient to extend from one to the other head of the spool, and the shape of the cylinder is such as to support the shell near each end. The rock- 50 shaft 7, directly under and parallel with the shaft e' and resting in bearings 16, has attached to it a lever 8 and arms 6 and 13. The lever 8 has a weight 10 or equivalent by which normally to turn the said rock-shaft

55 from the position of Fig. 2 into the position of Fig. 3 whenever the slide g' is moved to the left far enough to remove the shoulder 5 from the arm 6, the arm 13 at such time preferably meeting the girt A^2 and the arm 6 60 the finger 12 of the slide g' . When the slide g' is moved to the left, as described, to thus release the said rock-shaft 7, the lifting device or support m (shown as pivoted at 17 on an arm 18 preferably a part of the lever 8) 65 is moved from the position shown in Fig. 2 to that shown in Fig. 3, and, viewing Fig. 3, it will be seen that the shell h is lifted far enough to

remove its interior from contact with the cylinder e , and as a result thereof the said shell is supported by the lifting device, the 7c longitudinal center of the shell being then substantially coincident with the center of rotation of the cylinder or of the shaft e' , at which time the rotation of the shell and whatever rests on it is stopped.

75 For sake of lightness I have shown the cylinder e composed of two wheels or disks; but I may employ one wheel or roll as long as the shell or the barrel of the bobbin.

When the slide g' is moved to the left and 80 the arm 6 is stopped against the finger 12, the said arm, by acting against the shoulder 20, keeps the slide g' out, and the shell remains elevated or suspended and at rest.

85 When it is desired to drop the shell and start it in rotation, the operator, by engaging the handle n , fast on the rock-shaft 7, turns the said rock-shaft in a direction to lower the lifting device or support m and let the shell rest on the roll e , such movement of the rock- 90 shaft lifting the weight and removing the arm 6 from the shoulder 20, so that the spring g^2 acts to push the slide to the right and again place the shoulder 5 in place to hold the arm 6 and keep the weight lifted.

95 Believing myself to be the first to surround loosely a cylinder or roll by a cylindrical metallic or rigid shell which is adapted to be rotated by contact with the said cylinder, but which shell may remain at rest when it 100 is removed from contact with the said cylinder, I do not desire to limit my invention to the exact form of devices shown by which to effect the lifting of the said shell, nor do I desire to limit my invention to the exact 105 thing shown which is to be rotated by surface contact with the said shell.

It will be understood that an operative machine for winding will contain a number of cylinders and shells, they being duplicated 110 along one or both sides of the machine, as in the patent referred to. Soherein I have deemed it unnecessary to show but one cylinder, shell, and spool, and at one side of the frame, the shaft e' being broken off, the said shaft in 115 practice having at its right-hand end a cylinder such as shown at its left-hand end.

Any usual or suitable traverse-motion—such, for instance, as shown in the said patent—may be employed to guide the yarn onto 120 the spool.

I claim—

1. The combination, with a rotating cylinder and a surrounding rigid shell, of means to lift or suspend the said shell out of contact 125 from the said cylinder when it is desired to stop the rotation of the said shell, substantially as described.

2. The stands, the cheek-pieces to hold a spool, the shaft e' , a cylinder thereon, and the 130 shell h , surrounding the said cylinder, combined with means to lift or suspend the said shell, substantially as described.

3. The stands, the cheek-pieces to hold a

spool, the shaft e' , a cylinder thereon, and the shell h , surrounding the said cylinder, combined with means to lift or suspend the said shell and with the stop-motion slide and means to move it to enable the lifting device to act and lift the shell, substantially as described.

5 4. The rotating cylinder, combined with the hollow shell surrounding the said cylinder loosely and driving it by the contact of the

cylinder with the inner wall of the said shell, substantially as described.

In testimony whereof I have signed my name to this specification in the presence of two subscribing witnesses.

JOHN W. FOSTER.
